Primary Examiner — Ruth McInroy(74) *Attorney, Agent, or Firm* — RatnerPrestia(57) **CLAIM**The ornamental design for an exterior surface of a cyclone
receptacle, as shown and described.**DESCRIPTION**

FIG. 1 is a perspective view of an exterior surface of a cyclone receptacle showing my new design;
 FIG. 2 is a front elevation view thereof;
 FIG. 3 is a left side elevation view thereof;
 FIG. 4 is a rear elevation view thereof;
 FIG. 5 is a right side elevation view thereof;
 FIG. 6 is a top plan view thereof;
 FIG. 7 is a bottom plan view thereof;
 FIG. 8 is a perspective view of a second embodiment thereof;
 FIG. 9 is a front elevation view of FIG. 8;
 FIG. 10 is a left side elevation view of FIG. 8;
 FIG. 11 is a rear elevation view of FIG. 8;
 FIG. 12 is a right side elevation view of FIG. 8;
 FIG. 13 is a top plan view of FIG. 8; and,
 FIG. 14 is a bottom plan view of FIG. 8.

The broken lines which define the bounds of the claim or
environmental structure form no part of the claimed design.**1 Claim, 14 Drawing Sheets**| (56)	References Cited
